UNITED STATES PATENT OFFICE.

CHARLES C. HANSEN, OF EASTON, PENNSYLVANIA, ASSIGNOR TO INGERSOLL-RAND COMPANY, OF JERSEY CITY, NEW JERSEY, A CORPORATION OF NEW JERSEY.

OILING DEVICE FOR ROCK DRILLS.

Application filed November 29, 1921. Serial No. 518,630.

To all whom it may concern:

Be it known that I, CHARLES C. HANSEN, a citizen of the United States, and a resident of Easton, county of Northampton, and State 5 of Pennsylvania, have invented a certain Oiling Device for Rock Drills, of which the following is a specification accompanied by drawings.

This invention relates to fluid actuated 10 rock drills, more especially of the hammer type, but relates in particular to an improved oiling device for such machines which may be located in any convenient part of a machine but preferably in one of the 15 front end parts.

The objects of the invention are to improve upon such devices by simplifying and cheapening the construction and at the same 20 time secure an efficient oiling device located within the machine and capable of continuously supplying lubricating material to the 25 adjacent moving parts of the machine.

Further objects of the invention will hereinafter appear and the invention is shown in 30 one of its preferred forms in the accompanying drawings in which—

Figure 1 is a longitudinal sectional elevation of so much of a rock drill as will serve to make the invention clear;

Figure 2 is a detail plan view of a metallic 35 holder for a ring of absorbent material forming a part of the oiling device;

Figure 3 is a detail perspective view of a piece of absorbent material before it has assumed ring shaped form.

Figure 4 is a detail end view partly in 40 transverse section of the ring of absorbent material and the metallic holder assembled;

Figure 5 is a transverse sectional view on the line 5—5 of Figure 4, and

Figure 6 is a transverse sectional view on the line 6—6 of Figure 4.

Referring to the drawings, A represents the cylinder of a fluid actuated rock drill of 45 the hammer type having the front head B into which the lugged shank of the drill steel C extends in position to receive the blows of impact of the hammer piston D having the fluted forward extension E.

In this instance the rock drill is assumed 50 to have automatic rotation devices for the drill steel, a portion of the usual rifle bar being indicated at F. The forward extension E of the piston extends through the front cylinder washer G and the flutes H

engage the chuck nut J in the chuck K, suitably clutched to the chuck key L in the front head B. The ports and passages for the distribution of motive fluid for actuating the piston D in the cylinder A are omitted as 60 they are not necessary to an understanding of the present invention.

I have found that the lubricating material will be more uniformly and evenly distributed to the front end parts of the machine 65 by providing absorbent material of suitable character in an oil chamber or space in one of the front head parts. In accordance with the present construction the front cylinder washer G is provided with a circumferential 70 groove O communicating with the internal parts of the machine through the passages P and Q. Oil is supplied to the groove O by removing the oil plug R in the usual manner.

The absorbent material S may be in the 75 form of a piece of felt but as I do not desire to have this absorbent material fill the entire volume of the oil groove in the front cylinder washer G, I provide a metallic 80 holder T for the piece of felt preferably of thin sheet metal within which the felt is held. The metallic holder T and absorbent material S provide an oiling device in the form of a unit.

This metallic holder may be of any suitable form but I prefer to construct it with 85 apertures U to permit access of the oil to the felt, and projections V adapted to be bent over the sides of the felt strip to grip the strip and hold it on the holder. Shorter intermediate projections or guides W bear 90 against the sides of the oil groove in the front cylinder washer G and hold the absorbent material in a fixed position away 95 from the sides of the groove and consequently prevents it from becoming disintegrated due to vibration, and also permits free access of the oil to the material. Between the metallic holder T and the closure R I provide a space or chamber Z into which lubricating material is supplied so that it is entirely or partially filled, as desired.

In adjusting the ring of absorbent material and the holder in the machine, the metallic holder is bent around into ring shaped form as indicated in Figures 1 and 4 and a metallic tongue X on one end of the holder is adapted to be inserted in the slot Y at the other end of the holder after 100 105 110

the ring has been placed in the groove hole so that the holder and the absorbent material are retained in position in the groove. The absorbent material S becomes saturated with oil which is drawn out or fed into the moving parts of the machine in the front head during the operation of the machine. From time to time the oil plug R is removed and more oil is supplied to the groove O 10 as desired.

I claim:

1. In a rock drill, the combination of relatively movable members, a groove in one of said members remote from but in communication with the other of said members, an oiling device in said groove comprising a ring of absorbent material, and a perforated holder for said ring adapted to hold said ring away from the sides of said 20 groove.
2. In a rock drill, the combination of relatively movable members, a groove in one of said members remote from but in communication with the other of said members, an oiling device in said groove comprising a ring of absorbent material, a perforated metallic holder, projections on said holder for gripping said ring, guiding projections on said holder for holding said ring away 25 from the sides of said groove, and means for holding the meeting ends of said holder together.
3. In a rock drill, the combination with the cylinder and reciprocating piston, and

front cylinder washer through which the piston passes, of an oiling device for the front end parts of the machine, comprising a ring of absorbent material lying in an external circumferential groove of the front cylinder washer, said groove communicating with moving parts of the machine, means for supplying lubricating material to said groove, and a perforated metallic holder for said ring of absorbent material in the groove having projections for supporting the material in a fixed position in the groove, away from the sides thereof. 35

4. In a rock drill, the combination with the cylinder and reciprocating piston and front end parts of the machine, of an oiling device in the form of a unit, comprising a ring of absorbent material, a holder in the form of a perforated flexible strip encircling said absorbent material and means for holding the meeting ends of said perforated strip together, said unit lying in a groove in one of the front end parts of the machine, said groove communicating with the moving parts of the machine, a space or chamber being provided between the said unit and the closure for said groove means for holding said strip away from the sides of the groove and means for supplying lubricating material to said space or chamber. 50

In testimony whereof I have signed this specification.

CHARLES C. HANSEN.
